UNITED STATES PATENT OFFICE.

ALEXANDER HANVEY, OF STEUBENVILLE, OHIO, ASSIGNOR OF ONE-HALF
TO WILLIAM SCOTT, OF SAME PLACE.

TAG OR LABEL HOLDER.

SPECIFICATION forming part of Letters Patent No. 295,752, dated March 25, 1884.

Application filed February 11, 1884. (No model.)

To all whom it may concern:

Be it known that I, ALEXANDER HANVEY, a citizen of the United States, residing at Steubenville, in the county of Jefferson and State 5 of Ohio, have invented a new and useful Device for Attaching Labels to Mail-Bags and other Articles, of which the following is a specification.

My invention relates to improvements in 10 devices for attaching labels to mail-bags and other articles; and it consists in so bending a piece of wire as to admit of attaching and detaching labels readily, and also to hold them securely, when attached, without danger of 15 their being lost off.

The drawing is a perspective view of my invention.

The eye *a* is formed by bending the wire 20 into a circle of suitable size to allow of its being attached to the bag or other article to be labeled. The two ends of the wire *c* and *e* are then brought parallel to each other, a sufficient distance intervening between to allow 25 the label sufficient play to avoid its being held rigidly between them. At the proper distance from the eye *a* the end of the wire *c* is turned off at right angles and curved into the form of a hook, *x*, from which point the label hangs suspended when attached, while the wire *e* 30 passes through or within the curve forming

the hook *x*, a short distance, to prevent the label being lost off while the bag is being handled. The eye *a* acts also as a spring to bring the hook *x* and the straight wire *e* into proper positions again after a label has been 35 attached.

To attach a label, enter the end of the wire *c*, forming the hook *x*, into the hole of the label and follow the curve with the label, passing it over the straight wire *e* to the point 40 *x*, when the straight wire *e* will have resumed its natural position again from which it was moved by the placing of the label, acting as a keeper to prevent the label losing off. To remove the label, follow the curve of the hook 45 *x* with the label, passing it under the straight wire *e*.

I claim—

An improved spring tag or label holder, consisting of a single piece of wire bent to form 50 the eye *a*, and two parallel prongs, *c e*, one of which is bent at its end to form the hook *x*, and the other extending beyond the hook and adapted to rest therein, all substantially as set forth.

ALEXANDER HANVEY.
